tion of Delaware

Application December 1, 1945, Serial No. 632,151

8 Claims. (Cl. 257—3)

1

This invention relates to air conditioning. Many factors, such as transmission gains or losses, sun load, people, lights, etc., enter into the air conditioning of large buildings containing a plurality of enclosed areas since the heat loads affecting the different areas of the conditioned building necessarily vary. For example, in an office building, all of the offices having windows facing the east would be subjected to the heating effect of the sun early in the day whereas the heat load due to sun effect will decrease later in the day. Factors other than sun load are also of major importance. For example, if certain offices ordinarily contain several occupants while other offices contain only one occupant, the heat loads in such offices vary. In addition, some spaces may require illumination a major portion of the day while other offices require little or no illumination; necessarily, this affects the heat loads of such offices to a greater or lesser degree depending upon the degree of illumination required.

An air conditioning system in extensive use contemplates the separation of a building into zones in accordance with the various heat loads present in the rooms or offices thereof. In such system, air from the exterior of the building in a quantity adequate for ventilation requirements is treated at a central conditioning point remote from the areas to be conditioned to control the moisture content thereof in accordance with the requirements of the various zones, then treated in accordance with the factors of heat load in each zone, and distributed at relatively high static pressure and at relatively high velocity to a plurality of units disposed in and serving a plurality of areas to be conditioned in the various zones. The high pressure air supplied to each unit is discharged therein at high velocity, inducing a relatively great circulation of air withdrawn from the area served by the unit. The primary or high pressure air and the secondary or induced air are then supplied to the conditioned area to maintain a desired temperature therein. Tempering means such as coils or the like are disposed in the various local units to effect cooling or heating of air circulating through the unit as required; in the operation of the system, cold water is furnished to the tempering means under summer conditions, and warm water is furnished to the tempering means under winter conditions. It will be appreciated depending upon the heat load in each zone, cold or warm water may be supplied to any zone in winter or in summer. Under intermediate operating conditions,

2

it is necessary that some zones of the building be supplied with warm water while other portions of the building are supplied with cold water.

As stated above, this system is highly satisfactory and has entered into extensive use. It is somewhat complicated, however, due to the many controls required to condition adequately a building divided into numerous zones.

The chief object of the present invention is to provide a simplified method of operation of an air conditioning system of this general type.

An object of the present invention is to provide an improved air conditioning system in which zoning is eliminated, thus considerably decreasing the initial and operating costs of the system.

A further object is to provide a method of operation of an air conditioning system in which transmission losses or gains are compensated for by adjustment of the temperature of the conditioned air at a point remote from the areas to be conditioned and in which the variable heat gains such as sun load, lights, people, and the like are compensated for by varying individually in each area the temperature of the induced air in accordance with the variable heat factors present in such area.

A still further object is to provide a method of air conditioning in which a quantity of air sufficient for ventilation requirements is supplied to various areas, the air being first conditioned to compensate for transmission gains or losses in such areas, and in which the variable heat factors are compensated for by adjusting the dry bulb temperature or sensible heat of each area being conditioned in accordance with its individual requirements.

A still further object is to provide a method of air conditioning in which the conditioning medium supplied to the various areas to compensate for the variable heat factors is passed after passage through such areas in heat exchange relation with air to be conditioned and supplied to the various areas.

A still further object is to provide a method of air conditioning in which conditioning medium for induced air is supplied to the various areas, the temperature of the conditioning medium being adjusted at a point remote from the areas to be conditioned in accordance with the exterior temperature of the structure and in which a second supply of conditioning medium is provided for each of the areas being conditioned which is adapted to adjust the temperature of induced air in accordance with the variable heat factors present in each individual area.

The present invention relates to a method of air conditioning a building structure containing a plurality of enclosed areas in which the steps comprise supplying a quantity of air sufficient for ventilation requirements of the enclosed areas, conditioning air to control its moisture content while varying its sensible heat to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed areas in which it is disposed, varying the temperature of the induced air in each area to compensate for the effect of the variable sensible heat factors present in such area, mixing the streams of conditioned air and induced air, and discharging the mixture of conditioned air and induced air within the area to be conditioned. In some cases, the conditioning medium from the conditioning unit may be withdrawn and passed in heat exchange relation with air to be conditioned.

This invention further relates to a method of air conditioning a building structure containing a plurality of enclosed areas in which the steps comprise supplying a quantity of air sufficient for ventilation requirements of the enclosed areas, conditioning air to control its moisture content while varying its sensible heat to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a constant quantity of conditioning medium at a substantially constant temperature to a heat exchanger disposed in each unit, supplying a second quantity of conditioning medium at a predetermined temperature selected in accordance with the temperature exteriorly of the building to a second heat exchanger disposed in each unit, governing the temperature of the induced air by passing at least a portion thereof over the heat exchangers, adjusting the temperature of the induced air to compensate for the effect of the variable sensible heat factors present in each area by varying the quantity of conditioning medium passing through said first heat exchanger, mixing the streams of conditioned air and induced air, and discharging the mixture of conditioned air and induced air within the area to be conditioned.

The attached drawing illustrates a preferred embodiment of my invention in which:

Figure 1 is a diagrammatic view illustrating an air conditioning system embodying my invention;

Figure 2 is a fragmentary diagrammatic view of a portion of the system shown in Figure 1, illustrating a modification thereof;

Figure 3 is a fragmentary diagrammatic view of a portion of the system shown in Figure 1, illustrating a further modification thereof; and

Figure 4 is a diagrammatic view illustrating details of the conditioning unit.

Referring to the drawing, there is shown suitable air conditioning apparatus designated generally at 2, such apparatus being contained in a casing 3. The apparatus may be disposed in any suitable place in the basement, attic or a storage space of a building served thereby. A fan 4

is provided to draw air into casing 3 preferably from the outdoor atmosphere, the air being conditioned in any desired manner during its passage through casing 3, and then to discharge the conditioned air at relatively high static pressure into a primary high pressure air duct 5.

The conditioning apparatus illustrated at 2 may be of any desired type, and it is understood that the present invention is not limited with respect to the apparatus illustrated. As illustrated, apparatus 2 includes a plurality of dampers 6 through which air is drawn into casing 3 from the exterior of the building, a preheating coil 7 through which steam may be passed to preheat air passing into casing 3, a filter 8, sprays 9, a dehumidification coil 10, a plenum 11, and a reheating coil 12. In such apparatus the air is suitably conditioned in accordance with the requirements of the areas to be conditioned. In addition, reheating coil 12 is provided to adjust the sensible heat of the conditioned air to compensate for transmission gains or losses throughout the building being conditioned.

Conditioned primary air is forced through duct 5 by fan 4 and through ducts 13 to the conditioning units 14, shown in Figure 4, disposed in the various areas 15 to be conditioned. The conditioned primary air is discharged at relatively high velocity into units 14 and serves to induce a constant flow of secondary air within the unit from the area 15 being conditioned.

To control air conditioning apparatus 2, there is provided a thermostat T' actuated by a thermal responsive element such as a bulb 16 disposed exteriorly of the building being conditioned. Thermostat T' is adapted to actuate thermostat T which in turn operates valve 17 disposed in a steam line 18 which serves to conduct steam to reheating coil 12. The dry bulb temperature or the sensible heat of the conditioned air is adjusted in accordance with the dry bulb temperature exteriorly of the building in order to compensate for transmission gains or losses throughout the areas being conditioned. Bulb 19 disposed in the path of air having its dry bulb temperature adjusted to compensate for transmission gains or losses also actuates thermostat T to increase or to decrease the amount of steam passing into reheating coil 12. If desired, return air from the areas being conditioned may be fed through duct 20 (shown in dotted outline) into plenum 11 and mixed with the conditioned air before its temperature is adjusted by reheating coil 12.

I have shown a cooler 22 adapted to provide conditioning medium at a predetermined temperature for use within the system. The cooler 22 may comprise any suitable refrigerating apparatus adapted to cool a conditioning medium such as water. Water is conducted from cooler 22 through pipe 23 to pump 24 which forces the conditioning medium through pipe 25 to the dehumidifying coil 10 of apparatus 2. Water from dehumidifying coil 10 passes through pipe 26 to riser 27 adapted to supply the conditioning medium to the units 14 disposed in various areas 15. A heat exchange member 28 is disposed in each unit 14. Conditioning medium from heat exchangers 28 then passes through pipe 29 to a return riser 30 and pipe 31 to water cooler 22. A valve 32 is disposed in each pipe 33 leading from riser 27 to each heat exchanger 28. Valve 32 is controlled by means of a thermal element such as a bulb 34 disposed in the path of air induced within unit 14. It will be understood

damper 58 need not be employed when valve 32 is embodied in the system for in such case all the induced air is directed through heat exchanger 28.

It will be understood that instead of a water cooler 22 as described above a suitable cooling tower may be used as is well known in the art. If a cooling tower be used, valve 35 in line 36 is opened and valve 37 in line 28 is closed; in addition, valve 38 in line 31 is closed and valve 39 in line 39' is opened. Water from the cooling tower flows through line 36, valve 35 and pipe 28 as previously described. Upon its discharge from the various heat exchangers 28 it flows through pipes 29, return riser 30, line 31, and line 39' which returns it to the cooling tower.

In the method of operation of the air conditioning system illustrated in Figure 1, air is drawn through conditioning apparatus 2 from the exterior by means of fan 4 in a quantity sufficient to compensate for the ventilation requirements of the areas being conditioned. The air is conditioned in apparatus 2 to control the moisture content and sensible heat thereof whereby the sensible heat of the air is varied in accordance with the temperature exteriorly of the building to compensate for transmission gains or losses throughout the enclosed areas 15. The conditioned air is then supplied through primary duct 5 to ducts 13 which supply the conditioned air to units 14. Conditioned air is discharged in units 14 through nozzles or the like at a relatively high velocity. The relatively high velocity of the conditioned air within the unit induces a substantial flow of secondary air within the unit from the enclosed area 15 in which unit 14 is disposed.

Cooler 22 supplies conditioning medium within the range of 45° F. to 70° F. as required to pipe 28; pump 24 forces the conditioning medium through dehumidifying coil 10 and through pipe 26 to risers 27. Conditioning medium flows from riser 27 through valve 32 to heat exchange member 28 in unit 14. The induced air passes over heat exchange member 28; the temperature of the induced air is governed by its passage over the heat exchanger 28. The quantity of conditioning medium flowing through heat exchange member 28 is varied in accordance with the variable sensible heat factors present in the area by means of bulb 34 and valve 32 which control the amount of conditioning medium passing through heat exchanger 28. By this means the temperature of the induced air is varied to compensate for the effect of the variable sensible heat factors present in the areas. The streams of conditioned air and induced air are mixed in the unit, and the mixture is then discharged through a grille in the unit to the area to be conditioned.

While I have described the temperature of the induced air in each unit as being varied in accordance with the amount of conditioning medium flowing through heat exchanger 28, it will be understood the amount of conditioning medium flowing through heat exchanger 28 may be maintained substantially constant; the temperature of the induced air is then varied in accordance with the variable heat factors present in the area by means of a suitable damper 58 which varies the amount of induced air permitted to pass over heat exchanger 28. In other words, some portion of the induced air is passed over heat exchanger 28 while a second portion

of the induced air bypasses heat exchanger 28 as shown in Figure 4. In this case bulb 34 serves to actuate the actuating mechanism for the damper in accordance with the variable heat factors present in the area to determine the quantity of air passing over the heat exchanger.

In Figure 2 I have illustrated a modification of my invention which is particularly adapted for use during conditions of winter operation. As illustrated a heat exchanger 40 is added to apparatus 2. Conditioning medium, returning through line 31 from heat exchangers 28 of units 14 disposed in the various areas 15 to be conditioned, is passed through heat exchanger 40 in heat exchange relation with air from the exterior of the building drawn into apparatus 2. Under winter conditions the air entering apparatus 2 is colder than the cold conditioning medium returning through line 31. By placing the colder air and cold conditioning medium in heat exchange relation, the colder air is preheated and the cold conditioning medium is further cooled, thus reducing the operating cost of the system. The conditioning medium passes from heat exchanger 40 to cooler 41 where it is placed in heat exchange relation with water from a cooling tower passing through line 42 to cooler 41. The water from the cooling tower after its passage through cooler 41 is returned to the cooling tower through line 43. It will be understood by proper control of the valves in the various lines heat exchanger 40 and the cooling tower may be added to or cut from the system. When the heat exchanger 40 and the cooling tower are cut out of the system, cooler 22 functions as previously described.

In Figure 3 I have illustrated a modification of my invention adapted for use in certain geographic areas subject to excessive cold weather. In this case an additional heat exchanger member 44 is provided in each unit 14. The temperature of the conditioning medium conducted to exchanger 44 is varied in accordance with the exterior temperature of the building being conditioned. Thus under winter conditions hot water is supplied to exchanger 44 through line 45 and is discharged therefrom through line 46, while under summer conditions cold water is supplied to exchanger 44. Coil 28 in each unit is provided with water at a substantially constant temperature within the range of 45° F. to 70° F. selected without regard to exterior temperature. As the variable heat factors in each area being conditioned increase or decrease, valve 32 is actuated by bulb 34 to increase or to decrease the amount of conditioning medium flowing through heat exchanger 28. As described, a system such as illustrated in Figure 3 is particularly desirable for use in localities in which the temperature varies so greatly as to prevent the conditioned air alone effectively compensating for transmission gains or losses.

My invention provides a simplified method of operating an air conditioning system which eliminates the excessive initial and operating costs of systems heretofore used while permitting adequate results from a standpoint of air conditioning to be attained. The method of operation contemplated by the present invention may be applied to existing systems already installed in building structures or the system may be provided in new construction or buildings now without a system of air conditioning.

While I have described and illustrated a preferred embodiment of my invention, it will be understood my invention is not limited thereto

since it may be otherwise embodied within the scope of the following claims.

I claim:

1. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a quantity of conditioning medium at a temperature within the range of 45° F. to 70° F. and selected without regard to the exterior temperature to a heat exchanger disposed in each unit, governing the temperature of the induced air in each unit by passing at least a portion thereof over the heat exchanger, individually and automatically adjusting the temperature of the induced air in each unit to compensate for the effect of the variable sensible heat factors present in the area, mixing the streams of conditioned air and induced air, and discharging the mixture of conditioned air and induced air within the area to be conditioned to maintain a desired temperature therein.

2. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a quantity of conditioning medium at a substantially constant temperature selected without regard to the exterior temperature to a heat exchanger disposed in each unit, governing the temperature of the induced air in each unit by passing the induced air over the heat exchanger, varying the quantity of conditioning medium passing through the heat exchanger in accordance with the variable sensible heat factors present in each area thereby adjusting the temperature of the induced air in accordance with the variable heat factors present in each area, mixing the streams of conditioned air and induced air, and discharging the mixture of conditioned air and induced air within the area to be conditioned to maintain a desired temperature therein.

3. In the method of air conditioning a building structure containing a plurality of enclosed areas, the steps which comprise conditioning air to control its moisture content while varying its sensible heat to compensate for transmission gains or losses throughout the enclosed areas, supplying the conditioned air at high static pressure to conditioning units disposed in the enclosed areas,

discharging the conditioned air at high velocity within each unit to induce a substantial flow of secondary air within the unit from the enclosed area in which it is disposed, supplying a constant quantity of conditioning medium at a predetermined temperature to a heat exchanger disposed in each unit, passing at least a portion of the induced air over the heat exchanger in each unit to control the temperature thereof, varying the temperature of the induced air to compensate for the effect of the variable sensible heat factors present in each area by increasing or decreasing the quantity of induced air passing over the heat exchanger, mixing the streams of conditioned air and induced air, and discharging the mixture of conditioned air and induced air within the area to be conditioned to maintain a desired temperature therein.

4. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a quantity of conditioning medium at a predetermined temperature selected without regard to the exterior temperature to a heat exchanger disposed in each unit, governing the temperature of the induced air in each unit by passing at least a portion thereof over the heat exchanger, varying the temperature of the induced air in each unit to compensate for the effect of the variable sensible heat factors present in the area, mixing the streams of conditioned air and induced air, discharging the mixture of conditioned air and induced air within the area to be conditioned, withdrawing the conditioning medium from the conditioning units, and passing the withdrawn conditioning medium in heat exchange relation with air to be conditioned.

5. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a quantity of conditioning medium at a constant temperature selected without regard to the exterior temperature to a heat exchanger disposed in each unit, governing the temperature of the induced air in each unit by passing the induced air over the heat exchanger, varying the quantity of conditioning medium passing through the heat exchanger in accordance with the variable sensible heat factors present in each area thereby adjusting the temperature of the induced air to compensate for the effect of the variable

heat factors present in each area, mixing the streams of conditioned air and induced air, discharging the mixture of conditioned air and induced air within the area to be conditioned, withdrawing the conditioning medium from the conditioning units, and passing the withdrawn conditioning medium in heat exchange relation with air to be conditioned.

6. In the method of air conditioning a building structure containing a plurality of enclosed areas, the steps which comprise supplying a quantity of air sufficient for ventilation requirements of the enclosed areas, conditioning air to control its moisture content while varying its sensible heat to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a constant quantity of conditioning medium at a predetermined temperature to a heat exchanger disposed in each unit, passing at least a portion of the induced air over the heat exchanger in each unit to control the temperature thereof, varying the temperature of the induced air to compensate for the effect of the variable sensible heat factors present in each area by increasing or decreasing the quantity of induced air passing over the heat exchanger, mixing the streams of conditioned air and induced air, discharging the mixture of conditioned air and induced air within the area to be conditioned, withdrawing the conditioning medium from the conditioning units, and passing the withdrawn conditioning medium in heat exchange relation with air to be conditioned.

7. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a quantity of conditioning medium at a predetermined temperature selected without regard to the exterior temperature to a heat exchanger disposed in each unit, supplying a second quantity of conditioning medium at a predetermined tem-

perature selected in accordance with the temperature exteriorly of the building to a second heat exchanger disposed in each unit, governing the temperature of the induced air in each unit by passing at least a portion thereof over the heat exchangers, adjusting the temperature of the induced air to compensate for the effect of the variable sensible heat factors in such area by varying the quantity of conditioning medium passing through said first heat exchanger, mixing the streams of conditioned air and induced air, and discharging the mixture of conditioned air and induced air within the area to be conditioned.

8. In the method of air conditioning a building structure containing a plurality of enclosed areas, the steps which comprise supplying a quantity of air sufficient for ventilation requirements of the enclosed areas, conditioning air to control its moisture content while varying its sensible heat in accordance with the temperature exteriorly of the building to compensate for transmission gains or losses throughout the enclosed areas, supplying the conditioned air at high static pressure to conditioning units disposed in the enclosed areas, discharging the conditioned air at high velocity within each unit to induce a substantial flow of secondary air within the unit from the enclosed area in which it is disposed, supplying a substantially constant quantity of conditioning medium at a predetermined temperature selected without regard to the exterior temperature to a heat exchanger disposed in each unit, supplying a second quantity of conditioning medium at a temperature varying in accordance with the temperature exteriorly of the building to a second heat exchanger disposed in each unit, passing at least a portion of the induced air over the heat exchangers in each unit to control the temperature thereof, varying the temperature of the induced air to compensate for the effect of the variable sensible heat factors present in each area by increasing or decreasing the quantity of the induced air passing over the first heat exchanger, mixing the streams of conditioned air and induced air, and discharging the mixture of conditioned air and induced air within the area to be conditioned to maintain a desired temperature therein.
